[57] CLAIM

The ornamental design for a clip-on heat sink for electronic devices, as shown and described.

DESCRIPTION

FIG. 1 is a perspective view of a clip-on heat sink for electronic device being shown in broken lines for illustrative purposes only;

FIG. 2 is a front elevation view thereof;

FIG. 3 is a rear elevational view thereof;

FIG. 4 is a side elevational view thereof, looking toward the right side of the heat sink as it is shown in FIG. 1;

FIG. 5 is a side elevational view thereof, looking toward the left side of the heat sink as it is shown in FIG. 1;

FIG. 6 is a top plan view thereof; and

FIG. 7 is a bottom plan view thereof.

FIG. 2

FIG. 1

FIG. 3

FIG. 4

FIG. 5

FIG. 6

FIG. 7
